J.B. Emerson.
Screw Propeller.
Patented Mar. 8, 1834.

John Brown Emerson

Letters Patent Patented March 8, 1834.

The Schedule referred to in these Letters Patent and making part of the same containing a description in the words of the said John Brown Emerson himself of his improvement in the Steam Engine —

To all to whom it may concern. Be it known that I, John Brown Emerson of the City of New York, have invented certain improvements in the Steam Engine &c, and in the mode of propelling therewith, either vessels on the water, or Carriages on the Land and that the following is a full and exact description thereof. One object of my improvement is to substitute for the crank motion a mode of converting the reciprocating motion of a piston into a continued rotary motion, by a new combination of machinery for that purpose. This mode is applicable to an engine either with one or with two cylinders, and is carried into effect as follows. Along side of the cylinder place a shaft, the lower ends of which may revolve in a step on the platform, or foundation upon which the cylinder stands in which case it must be somewhat longer than twice the length of the cylinder, as it must stand above it to a height somewhat greater than the length of the stroke of the piston, sometimes however, this shaft may have its lower gudgeon only a small distance below the upper end of the cylinder whence it must extend above it as before. The upper gudgeon must of course be mounted by a suitable frame. This shaft is to stand parallel to the piston rods, from which it is to receive its rotary motion, upon the upper end of this shaft, above the top of the cylinder, there is to be placed a solid cylinder of wood, or of any other convenient substance of such diameter as shall cause its periphery to come nearly into contact with the piston

363

rod, of the whole length, where the piston is moved. The solid cylinder above described is to be made to move in the following manner. In the groove in it which commences near its lower end and having spirally, extends half way round it, the time it reaches nearly to the upper end, or to a distance spirally, equal to the stroke of the engine, from that point it goes down around the opposite half and returns into itself at the point of beginning, upon the upper side of the piston against its sides, a piston roller, which is to work in the groove in the solid cylinder, the piston rod being between parallel guide pieces by which it is kept in its proper place, and its tendency to turn round by the action of the roller in the groove is checked. When the piston is down, this piston roller will stand in the V formed junction of the grooves on the opposite sides, and as it rises it will open a passage to the upper junction, give half a revolution to the solid cylinder and in descending will complete the revolution by the action of the piston roller on the other portion of the groove. — When two steam cylinders are used, they are to be placed parallel to each other and at such distance apart that the pistons of each may in like manner act upon the solid cylinder, the piston of one being up, when the other is down. The boiler, the steam pipe, the valves for the admission and discharge of steam and other appendages may be similar to some of those already in use. From the revolving shaft already described a rotary motion may be communicated to parallel wheels, steam carriages, or other objects. As it is my intention in general to place my cylinders and revolving shaft vertically, I communicate motion to the horizontal shaft of a parallel wheel by means of belt gears, wheels near the lower end or at any convenient part of the shaft and by similar gearing carriages may be pro-

filled upon Rail or ordinary Roads. When used for Steamboats I employ an improved spiral paddle wheel differing essentially from those which have hitherto been essayed. This spiral is made of taking a piece of metal of such length as to extend the spiral propeller to be, and of a suitable width, say for example eighteen inches; this I bend along the centre so as to form two sides, say of nine inches in width standing at right angles or nearly so to each other, and give to it longitudinally the spiral curvature which I wish. of these pieces I then take two or more, and fix them onto the outer end of the paddle shaft by means of arms of a suitable length, say of two feet more or less, in such a position that the troughs formed give to the longitudinal edge shall be effective in acting upon the water. It must be entirely under water and operate in the direction of the Boat's way. Instead of metal the spiral propeller may be formed of wood worked into the proper form the shape and not the material thereof being the only point of importance. -- Where a capstan is required as on board of a Steam Boat, I allow the upper end of the vertical shaft before described to pass up through the deck of the vessel, and attach the capstan thereto so that it may be made to revolve by the action of the shaft, using such fly wheels and pallets to connect the shaft and the capstan as will allow of their being conveniently engaged and disengaged. What I claim is my invention and for which I ask a patent is the substituting for the crank in the reciprocating engine a grooved cylinder operating in the manner hereinbefore described by means of a connection with the piston rod, together with all the variations of which this principle is susceptible. For example a bar of metal may be bent in the form of the groove and attached to the rotating shaft, and friction will occur on the piston rod and embrace this on each side producing an effect similar to that produced by the groove. --

Drawing

1053
I also claim the spiral propelling wheel constructed and operating in the manner in which I have set forth and likewise the application of the revolving vertical shaft to the turning of a capstan on the deck of a vessel. Not intending in either of these parts to confine myself to precise forms or dimensions but to vary them in such manner as experience or convenience may dictate, whilst the principle of action remains unchanged, and similar results are produced by similar means.
